(57) **CLAIM**

The ornamental design for beverage dispenser, as shown and described.

DESCRIPTION

FIG. 1 is a front perspective view of a beverage dispenser embodying our new design;

FIG. 2 is a front view thereof;

FIG. 3 is a rear view thereof;

FIG. 4 is a top view thereof;

FIG. 5 is a bottom view thereof;

FIG. 6 is a side view thereof as seen from the right-hand side of FIG. 2;

FIG. 7 is a side view thereof as seen from the left-hand side of FIG. 2; and,

FIG. 8 is a rear perspective view thereof.

The broken lines in FIGS. 1-8 represent portions of the beverage dispenser that form no part of the claimed design.
